Primary Examiner — Calvin E Vansant
Assistant Examiner — Giang Hoang Tran(57) **CLAIM**

The ornamental design for an e-bike, as shown and described.

DESCRIPTION

FIG. 1 is a front, right and top perspective view of an e-bike showing my new design;

FIG. 2 is a rear, left and bottom perspective view thereof;

FIG. 3 is a right view thereof;

FIG. 4 is a left view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged view of a portion labeled as 9 on FIG. 1;

FIG. 10 is an enlarged view of a portion labeled as 10 on FIG. 1;

FIG. 11 is an enlarged view of a portion labeled as 11 on FIG. 1;

FIG. 12 is an enlarged view of a portion labeled as 12 on FIG. 2;

FIG. 13 is an enlarged view of a portion labeled as 13 on FIG. 2; and,

FIG. 14 is an enlarged view of a portion labeled as 14 on FIG. 2.

The dash-dot lines show the bounds of the enlarged portions in FIGS. 1 and 2 form no part of the claim.

1 Claim, 14 Drawing Sheets(56)
